INVENTOR

George E. Krause

Dr. George Merck, Raymond Bond
ATTYS.

UNITED STATES PATENT OFFICE.

GEORGE E. KRAUSE, OF CANTON, OHIO.

BOX.

1,335,787.

Specification of Letters Patent.

Patented Apr. 6, 1920.

Application filed December 12, 1919. Serial No. 344,335.

To all whom it may concern:

Be it known that I, GEORGE E. KRAUSE, a citizen of the United States, residing at Canton, in the county of Stark and State 5 of Ohio, have invented a new and useful Box, of which the following is a specification.

This invention relates to boxes and more especially to boxes formed of sheet metal 10 and designed to contain small articles such as medicinal tablets or the like and more particularly to boxes of this character provided with means whereby the lid may be easily and readily removed from the box.

It is of course well known that a great majority of small sheet metal boxes such as are generally used for medicinal tablets and the like are very hard to open and often when the lid is removed from the box it requires such an effort on the part of the user 20 that the tablets or other contents of the box are spilled and it is very common practice for persons buying such articles to ask the druggist or storekeeper to place the tablets 25 or other articles in a paste board box or paper envelop in order that they will not have the difficulty of removing the box lid in order to have access to the contents thereof.

The objects of this invention are to provide a sheet metal box of the character described with a removable lid and means for easily removing the lid without extraordinary effort upon the part of the user 30 at the same time preventing the spilling of the contents of the box when the lid is removed; to generally improve and simplify the construction of boxes of this character.

With these objects in view the invention 40 consists in the novel construction and arrangement of parts, hereinafter described, illustrated in the accompanying drawings, and particularly pointed out in the appended claim, it being understood that various 45 changes in the form, proportions, size and minor details of construction may be made within the scope of the appended claim, without departing from the spirit or sacrificing any of the advantages of the invention.

The invention thus set forth in general terms is illustrated in the accompanying drawings forming part hereof, in which—

Figure 1 is a sectional view through a 50 box embodying the invention showing the lid in the closed position.

Fig. 2 is a similar view showing the operation of the device, the lid being loosened and ready for removal from the box.

Fig. 3 is a sectional view through a 60 slightly modified form of the box showing a construction of box which may be opened from either end.

Fig. 4 is a similar view of a still further modification.

Fig. 5 is a plan view of a sheet from which 65 the blanks forming the boxes are cut showing a means of cutting the boxes to economize the material.

A practical embodiment of the invention 70 is disclosed in the accompanying drawings, forming a part of this specification in which similar numerals of reference indicate corresponding parts throughout the several views.

Referring first to the construction illustrated in Figs. 1, 2 and 5 a box is illustrated which may be opened by pressure upon one end of the box and lid. The box 1 is formed of sheet metal preferably 80 rectangular in shape and provided upon opposite longitudinal sides near one end with the upwardly protruding lugs 2 upon which the under surface of the lid 3 rests when the box is in the closed position.

When it is desired to open the box illustrated in the figures above mentioned it is only necessary to grasp the end of the box adjacent the lugs 2 between the thumb and fingers and exert a slight pressure thereon, 90 causing the lid to rock upon the lugs 2 into the positions shown in Fig. 2 raising the other end of the lid sufficiently to allow its being easily removed.

It should be noted that this operation 95 will not suddenly remove the lid from the box and jar the box in any way to allow the contents of the box to spill therefrom. This overcomes the difficulty found in boxes of this character which are now in general 100 use wherein considerable effort is required to open the lid or remove it from the box, the contents of the box being often spilled in the process of opening the lid.

In Fig. 5 is illustrated a portion of a 105 sheet of metal showing the manner in which the boxes are stamped therefrom to economize the metal. The blank from which each box is formed is indicated by the numeral 4, the lugs 2 being shown stamped from the 110 edge portions of the adjacent blanks forming notches 5 in the adjacent blanks which

notches are not of sufficient depth to interfere with the operation of the box or cover.

In Fig. 3 is shown a modified form of the box which may be opened from either end, 5 the box 1^a being provided upon each longitudinal side edge with a pair of spaced lugs 2^a, one of said lugs being located near each end of the box, the lid 3 when in the closed position rests upon both of these lugs and 10 may be removed in the manner illustrated in Fig. 2 by a pressure upon either end thereof of rocking the lid upon the lugs adjacent the end at which the pressure is applied.

In Fig. 4 is illustrated a still further modification in which the box 1^b is provided upon 15 each longitudinal edge with a central lug 2^b extending to a point near each extremity of the box, the lid 5 resting upon this lug when in this closed position. By applying 20 pressure to either end of the lid it will be rocked upon the lug 2^b the operation being the same as in the device shown in Fig. 3.

It will thus be seen that a box is provided in which the lid, although fitting 25 snugly upon the box, may be easily and readily opened and removed therefrom by applying a slight pressure upon the end portions of the box and lid causing the lid to be raised at the other end sufficiently 30 to allow its easy removal from the box preventing the lid from suddenly flying open and the contents from the same being easily spilled.

The box formed as above described and 35 illustrated in the accompanying drawings may be easily opened by any one, no skill being required to remove the lid from the

box. It will be seen that a person may easily open this box although wearing gloves at the time, it not being necessary 40 to remove the gloves in order to open the box as is generally necessary in the usual box of this character.

Although the box is illustrated as being of oblong shape it will of course be understood that the invention may be applied to a square box or to an oval box with the same result, no change in the invention being necessary to apply it to boxes of this shape. 45

Although the drawings and above specification disclose the best mode in which I have contemplated embodying my invention I desire to be not limited to the details of such disclosure, for, in the further practical application of my invention, many changes 50 in form and construction may be made, as circumstances require or experience suggests, without departing from the spirit of the invention, within the scope of the appended claim. 55

I claim:

A rectangular sheet metal box, having vertical side walls provided with straight upper edges, upwardly protruding lugs upon opposite side edges of the box near 60 one end thereof, and a detachable, tight fitting cover normally resting upon said lugs and upon the opposite end edge of the box and arranged to be loosened by applying pressure upon the box and lid at the end 70 adjacent to the lugs.

In testimony that I claim the above, I have hereunto subscribed my name.

GEORGE E. KRAUSE.
